CLAIM

The ornamental design for an athletic belt with insert, as shown and described.

DESCRIPTION

FIG. 1 is a front perspective view of the athletic belt with insert of the present invention showing our new design.

FIG. 2 is a front side elevation view thereof;

FIG. 3 is back side elevation view thereof;

FIG. 4 is a side elevation view thereof;

FIG. 5 is another side elevation view thereof;

FIG. 6 is a top plan view thereof;

FIG. 7 is a bottom plan view thereof;

FIG. 8 is a perspective view of FIG. 1 shown in use;

FIG. 9 is a perspective view showing how the insert is placed into the belt; and,

FIG. 10 is a perspective view of FIG. 9 in use.

(Continued)

In the drawings, the evenly-spaced broken lines depicts stitching and forms part of the claim. The dash-dot-dash lines represent environment and forms no part of the claimed design.

1 Claim, 8 Drawing Sheets
